UNITED STATES PATENT OFFICE

167,063

TRANSMISSION LINE ARMOR ROD END
CLAMP

Samuel Warnock, Seattle, Wash., assignor to
Boeing Airplane Company, Seattle, Wash., a
corporation of Delaware

Application January 25, 1952, Serial No. 18,211

Term of patent 14 years

(Cl. D54—2)

To all whom it may concern:

Be it known that I, Samuel Warnock, a citizen of Canada, residing at Seattle, in the county of King and State of Washington, have invented a new, original, and ornamental Design for a Transmission Line Armor Rod End Clamp, of which the following is a specification, reference being had to the accompanying drawing, forming a part hereof.

Figure 1 is an enlarged perspective view of a transmission line armor rod end clamp, embodying my new design;

Figure 2 is a plan view thereof;

Figure 3 is an end view thereof; and

Figure 4 is a side view thereof.

The fragmentary views of an armor rod and transmission line disclosed in dotted lines as shown in Figure 2 are for illustrative purposes only.

I claim:

The ornamental design for a transmission line armor rod end clamp, as shown and described.

SAMUEL WARNOCK.
